UNITED STATES PATENT OFFICE.

LOUIS JENSEN, OF CHICAGO, ILLINOIS, ASSIGNOR TO UNITED AUTOGRAPHIC REGISTER COMPANY, OF CHICAGO, ILLINOIS, A CORPORATION OF ILLINOIS.

REGISTERING PAPER WEBS.

Application filed January 25, 1926 Serial No. 83,645.

My present invention relates to means for adjusting, registering and arresting the feed of webs of paper and has more particular reference to a structure wherein several strips 5 of paper are adapted to be moved across a writing bed where manifold copies are produced, after which the strips are adapted to be severed at the forward end of the machine into equal lengths.

10 In certain types of typewriting machines, such as the Elliott-Fisher machine, the writing is done upon a flat bed upon which the paper is clamped in any suitable manner. It is the purpose of my invention to provide means that will permit continuous strips or 15 webs of paper to be threaded upon such a writing bed, said webs being provided with apertures or perforations disposed longitudinally of the web, and the perforations utilized in combination with the elements of 20 my invention for the purpose of arresting the feed of the paper and also for registering the superposed strips. In such devices the webs of paper frequently have tickets or 25 blanks printed thereon between transverse perforations and the tickets are to be filled in by the operator, after which the paper is drawn forward and severed upon a suitable tearing blade. My present mechanism is de- 30 signed for the purpose of determining the lengths of the strips to be pulled out of the machine by arresting the pull-out movement at the desired location, and also for maintaining and registering the tickets in the super- 35 posed order, so that the writing will appear in the proper places on each ticket of a set.

The objects of my invention are to provide devices for arresting the feed of the strips and for registering the tickets, which devices 40 are dependable in operation, and which are so constructed that they may be readily installed upon a machine already in use. The mechanism is novel and simple in construction and is easy to operate, and on account of 45 its simplicity and its few parts it may be readily manufactured and sold for a moderate price. The mechanism also effects a very considerable saving of time for the person using the same as the operation of the parts 50 are to a large extent automatic in their functions.

I prefer to carry out my invention and to accomplish the divers objects thereof in substantially the manner hereinafter described 55 and as more particularly pointed out in the

claims, reference being here made to the accompanying drawings that form a part of this specification.

In the drawings:

Figure 1 is a top plan of the writing bed 60 and upper frame portion of a well known type of writing machine, showing my invention installed thereon.

Figure 2 is a front edge view thereof.

Figure 3 is a transverse section on line 65 3-3 of Figure 1 drawn to a larger scale with the structure condensed in width.

Figure 4 is a vertical section on line 4-4 70 of Figure 3, looking to the left in the direction of the arrows.

Figure 5 is a vertical section on line 5-5 75 of Figure 3, looking to the right in the direction of the arrows.

The drawings are in a sense schematic for the purpose of illustrating a typical or preferred form in which my invention may be constructed and I have employed similar reference characters to designate like parts wherever they appear throughout the several 80 views of the drawings.

My invention is illustrated as installed on the well-known Elliott-Fisher machine, the upper portion of the frame of which consists of parallel side rails 10 that provide a track upon which the shiftable typewriting machine (not shown) is mounted, said rails being connected at their forward ends by a cross-piece 11 and also intermediate their ends by a platen supporting bar 15. The platen, which is in the form of a flat writing-bed or table 14, extends from the front cross-piece 11 to the supporting bar, and it is of a width to be positioned horizontally between the side-rails 10. A movable clamping and cutting-blade 13 extends transversely across the front end of the platen 14, and guide clamps 16, operated in any suitable manner, press against the edges of the paper at the rear of the platen so as to maintain the paper flat on the platen, the clamps being releasable so that the paper may be moved when desired. The paper webs A and B, which are schematically shown in the drawings, are wound together in the form of a roll 18 and are provided with longitudinally extending 90 rows of punch-holes α for conveniently filing the severed tickets, which punch-holes are utilized in the operation of my web controlling devices.

To the inner faces of the side-rails 10, I se- 110

cure elongated metal strips 5 that extend from back of the platen rearwardly towards the end of the sills and in the upper edges of these strips are provided spaced transverse slots or 5 serrations 6, so that my web controlling mechanism may be adjusted towards or away from the platen according to the size of the ticket on the web or the distance between the longitudinal punch-holes a in said web. Coacting 10 with these serrated strips is an adjustable frame consisting of short horizontal side members 7 that are positioned longitudinally alongside the strips 5 and are connected across their upper edges by a cross-piece 12 the ends 15 of which latter extend beyond the vertical planes of the side members 7 so that said overhanging ends will rest upon the upper edges of said strips 5 and thereby support the adjustable frame. In order to maintain the adjustable frame against movement upon the strips 5 I have provided the frame with L-shape latches the members 8 of which are vertically disposed and are adapted to engage with the respective transverse slots or serrations 6 in the upper edges of the strips 5. Back of the cross-piece 12 I provide a plurality of rods or rollers 17, which are mounted at their ends in journaling bars 9 that are pivotally carried by the adjustable frame, and the 20 webs or strips of paper are separated and threaded over these rollers 17 from a large roll 18 of the paper. The roll of paper 18 is mounted in and rotates upon a spindle 19 supported in the lower portions of depending 25 arms 20 that are secured at their upper ends to side members 7 of the adjustable frame. Associated with the rollers 17 is a stationary transverse rod 21 on which are mounted the adjustable paper guides 22 for correctly positioning the webs in alinement with the clamps 16, which latter act also as guides when the strips are being withdrawn over the platen. For convenience, it is preferred to wind two or 30 more webs together on a single roll 18 and then 35 separate the webs as they pass over the rollers 17 as in Figure 5. When tickets of greater or less length are employed or the punch-holes are changed as to their longitudinal spacing, the adjustable frame may be fitted off the serrated strips 5 and shifted to the desired position where it is lowered to the strips 5 and the latch members 8 will enter the proper transverse slot 6 and maintain the frame against accidental longitudinal movement on the 40 strips 5.

The cross-piece 12 is provided intermediate its ends with a plurality of slots 23 that are elongated transversely of the cross-piece, and above this cross-piece and spaced therefrom a 45 slight distance so as to provide a slot therebetween I have placed a removable retainer plate 24 having transversely elongated slots 25 that correspond and align with the slots 23 in the cross-piece 12. One end of the retainer plate 60 is provided with a notch or recess 26 to engage

the shank of a headed bolt 27 and at its opposite end it is pressed down between spring lips 28 so as to removably maintain it in position.

A horizontal rock-shaft 29 has its ends journaled in apertures formed in the depending arms 20 and it is provided intermediate its ends with radially projecting members that extend upwardly into the slots to engage with the perforations in the paper when said perforations come into alinement therewith and when the paper is being moved these radial members are retarded to a certain extent and press upwardly against the under surface of the lowermost strip. These members may be of any suitable construction and I prefer to employ pins that are telescopically yielding and consist of elongated upstanding wire rods 30 that project from the rock-shaft 29 towards and are in alinement with the apertures 23 and 25 heretofore mentioned. Mounted upon these rods are telescoping tubes 31 that are preferably closed at their ends which extend into the apertures or slots 23 and 25 and below the cross-piece 12 have lateral elements or flanges 32 in the form of annular disks. Coiled expansion springs 33 surround the tubes and rods and extend between the flanges 32 and the rock-shaft 29 so that the ends of the pin members are constantly urged in an upward direction into the slots or apertures 23 and 25. When the paper or webs is being pulled from the forward portion of the machine the tubular portion of the pin members will have been returned so that they press upwardly against the paper until a set of apertures or punch-holes in the paper come into registration with the slots whereupon the pin members will be elongated and enter the punch-holes in the paper and will retard and stop the further withdrawal of the webs. The rock-shaft 29 has a coiled spring 34 surrounding it adjacent one of its bearings, one end of said spring being secured to a screw 35 on the adjacent arm 20 and its other end is secured to a collar 36 adjustably secured on the shaft so as to regulate the tension of the spring. The tendency of this spring is to urge the rock-shaft 29 in a rearward direction and consequently keeps the upper ends of the pin members in the rearward portions of the slots 23 and 25 as seen in Figure 1 and, as soon as the pin members have entered the punch-holes in the paper, the shaft 29 will begin to rotate against the spring 34 thus retarding the movement of the paper which will be felt by the operator who will immediately discontinue further pull upon the paper thereby permitting the pin members to return to the ends of the slots.

For the purpose of assisting in registering the webs I have provided means for vibrating the rock-shaft, which means consists of an arm 37 adjustably secured by means of a collar 38 to the end of the shaft opposite the spring 34. The lower end of this arm has pivotal connection with a punch-rod 39

secured thereto by a wing-nut 40, which push-rod extends forwardly under the platen 14 and the forward transverse bar 11 of the frame where the outer portion of the push-rod is supported in a guide at the lower end of a bracket 41 secured to the front end of the right-hand side 10 and beyond this guide is provided with a head or button 42 for conveniently operating same. When the paper strips or webs have been engaged, by the pin members entering the perforations, said webs may be moved or jerked back and forth in a horizontal plane in their direction of movement between the cross-piece 12 and plate 24 by reciprocating the push-rod 39 as rapidly as desired back and forth. This vibratory action will bring the apertures in the webs into complete registry or alinement with each other. It will be understood that this vibrating movement of the webs may be readily accomplished because of the fact that the apertured cross-piece 12 is spaced from the adjacent edge of the platen 14 and guide clamps 16 which provides an open space through which the paper is unsupported.

When it is desired to withdraw the webs by moving them forwardly toward the front of the machine it is necessary to withdraw the pin members from the perforations, and I prefer to do this by providing a rock-shaft 43 the ends of which are journaled in the horizontal side members 7 of the adjustable frame and which shaft intermediate its ends is provided with radially projecting flat fingers 44 that have off-set portions so that their outer portions will lie flat against the under-side of the cross-piece 12 alongside the apertures and above the flanges 32 of the pin members. When this shaft 43 is rocked the fingers 43 move downwardly (as shown in dotted lines in Figure 4) and pressing against the flanges 32 will move the latter against the springs 33, thus withdrawing the projected ends of the tubes 31 and retracting the pin members from the perforations in the webs so that the latter may be withdrawn upon releasing the clamps. At one end the rock-shaft 43 is surrounded by a coiled spring 45 having one of its ends connected with the side rail 10 and its other end secured to a collar 46 adjustably mounted upon the rock-shaft so as to regulate the spring tension as desired. An operating arm 47 is mounted upon the opposite end of the rock-shaft 43 by means of an adjustable collar 48 and at its lower end said arm has pivotal connection with a push-rod 49 secured thereto by a wing-nut 50. This push-rod extends below the platen 14 and front cross-piece 11 to the front end of the machine where it is mounted in a guide in the lower end of the bracket 51 secured to the left-hand side rail 10 of the frame; and upon its extended end the push-rod is provided with a head or button 52 by which it may be conveniently operated.

Stop-pins 53 and 54 are provided respectively for the operating arms 47 and 37 in order to prevent their movements too far in one direction. The push rods 39 and 49 are each formed in two sections with the adjacent ends overlapped and provided with a plurality of holes 39^a and 49^a in the respective rods that are brought into registry and the two sections secured together each by a pair of screws 39^b and 49^b. This permits the shortening or lengthening of the push-rods wherever the paper registering mechanism is adjusted towards or away from the platen.

From the foregoing it will be seen I have provided a dependable structure that will permit a plurality of webs of perforated paper to be fed across the flat bed or writing tablet of the machine, which webs will be stopped or arrested in their withdrawal movements at the end of each successive set of tickets, and the webs may be readily released by withdrawing the pin members from the perforations. The webs may be also vibrated back of the clamping members on the writing bed so as to register the superposed tickets and maintain them in registry until it is desired to move them onto the writing bed. It will be seen that I have provided four of the wire rods 30 on the rock shaft 29, only two of which are complete with the tubes 31 and springs 33, and there are four sets of slots 23 and 25 in the cross members 12 and 24. This permits of the spacing of the pin-members for punch-holes that are farther apart or closer together and it also permits of the use of more than two pin-members in the event such is desired.

What I claim is:-

1. A device of the kind described comprising a suitable support, a horizontal table positioned thereon across which perforated paper webs are moved, a frame mounted adjustable towards and away from said table, said frame including a cross-piece past which the paper is moved to the table, a rock-shaft on said frame, pin-members projecting from said rock-shaft into coaction with said cross-piece whereby to arrest the movement of the paper towards the table by engagement in perforation in the webs.

2. A device of the kind described comprising a writing table, a support therefor, a frame adjustably mounted on said support and spaced from the table, spaced plates providing a guide passage on said frame through which the paper webs pass to the table, said plates being transversely apertured, a rock-shaft journaled in said frame below said plates, yieldable pin-members carried by said rock-shafts and extending into the apertures in said plates, and means for retracting said pin-members out of said apertures.

3. A device of the kind described comprising a writing table, a support therefor, a frame adjustably mounted on said support

and spaced from the table, spaced plates providing a guide passage on said frame through which the paper webs pass to the table, said plates being transversely apertured, a rock-shaft journaled in said frame below said plates, yieldable pin-members carried by said rock-shafts and extending into the apertures in said plates, and means for rocking said shaft, whereby to vibrate said pin-members back and forth in said apertures.

4. A device of the kind described comprising a writing table, a support therefor, a frame adjustably mounted on said support and spaced from the table, spaced plates providing a guide passage on said frame through which the paper webs pass to the table, said plates being transversely apertured, a rock-shaft journaled in said frame below said plates, yieldable pin-members carried by said rock-shafts and extending into the apertures in said plates, and means for rocking said shaft, whereby to vibrate said pin-members back and forth in said apertures, and means for retracting said pin-members out of said apertures.

5. A device of the kind described comprising a writing table, a support therefor having side-rails extending from said table, a frame adjustable longitudinally on said rails towards and away from said table, means for mounting a roll of longitudinally perforated paper on said frame, an apertured cross piece past which the paper is moved to the table, and a pair of automatically returnable rock-shafts journaled in said frame, one of said shafts provided with retractable means that coat the apertures in said cross-piece to arrest movement of the paper through the perforation therein, and the other shaft is provided with devices that engage said retractable means and cause the same to withdraw from the paper perforations.

6. A structure for attachment to a flat bed writing device comprising a frame having side-pieces, an apertured cross-piece, and arms pendent from said side pieces, for journaling a paper roll in said arms, guide rollers carried by said side-pieces and over which the paper is threaded and extended past the cross-piece to the bed of the writing device, a rock-shaft journaled in said frame, pin members on said rock-shaft and extended into the apertures in said cross piece to arrest movement of the paper through the perforations therein, and means for withdrawing said pin-members from the paper.

7. A structure for attachment to a flat bed writing device comprising a frame having side-pieces, an apertured cross-piece, and arms pendent from said side pieces, for journaling a paper roll in said arms, guide rollers carried by said side-pieces and over which the paper is threaded and extended past the cross-piece to the bed of the writing device, a rock-shaft journaled in said frame, re-

tractable pin members on said rock-shaft and extended into the apertures in said cross piece to arrest movement of the paper through the perforations therein, a second rock-shaft journaled in said frame, and means actuated by the second rock-shaft for causing said pin members to withdraw from the paper.

8. A structure for attachment to a flat bed writing device comprising a frame having side-pieces, an apertured cross-piece, and arms pendent from said side pieces, for journaling a paper roll in said arms, guide rollers carried by said side-pieces and over which the paper is threaded and extended past the cross-piece to the bed of the writing device, a rock-shaft journaled in said frame, retractable pin members on said rock-shaft and extended into the apertures in said cross piece to arrest movement of the paper therein, a second rock-shaft journaled in said frame, spaced figures projecting from said second rock-shaft and engaged with said pin members, and means for moving said second rock-shaft whereby to cause said pin-members to withdraw from the paper.

9. A structure for attachment to a flat bed writing device, comprising a frame having side-pieces, an apertured cross-piece, and arms pendent from said side pieces, means for journaling a paper roll in said arms, guide rollers carried by said side-pieces and over which the paper is threaded and extended past the cross-piece to the bed of the writing device, a rock-shaft journaled in said frame, pin members on said rock-shaft and extended into the apertures in said cross pieces to arrest movement of the paper through the perforations therein, means for withdrawing said pin member from the paper, and means for actuating the first rock-shaft to vibrate said pin-members while engaged in the perforations in the paper.

10. A structure for attaching to a flat bed writing device comprising a frame having side-pieces, an apertured cross-piece, and arms pendent from said side pieces, for journaling a paper roll in said arms, guide rollers carried by said side-pieces and over which the paper is threaded and extend past the cross-piece to the bed of the writing device, a rock-shaft journaled in said frame, retractable pin member on said rock-shaft and extended into the apertures in said cross-piece to arrest movement of the paper through perforations therein, a second rock-shaft journaled in said frame, means actuated by the second rock-shaft for causing said pin member to withdraw from the paper, and means for actuating said first rock-shaft to vibrate said pin member while engaged in perforation of the paper.

11. A structure for attachment to a flat bed writing device comprising a frame having side-pieces, an apertured cross-piece, and arms pendent from said side-piece, for jour-

naling a paper roll in said arms, guide rollers carried by said side-pieces and over which the paper is threaded and extended past the cross-piece to the bed of the writing device, a rock-shaft journaled in said frame, retractable pin-members on said rock-shaft and extended into the apertures in said cross piece to arrest movement of the paper through perforations therein, a second rock-shaft journaled in said frame, spaced fingers projecting from said second rock-shaft and engaged with said pin members, means for moving said second rock-shaft whereby to cause said pin members to withdraw from the paper, and means for actuating said first rock-shaft whereby said pin members are vibrated while in the perforations in the paper.

12. A device for controlling webs that are perforated longitudinally comprising a web supporting writing table, an apertured frame spaced back of the table and past which the webs are moved to the table, said frame being bodily adjustable towards and away from the table, pin members positioned in the apertures of said frame and adapted to enter the perforations in the portions of the webs unsupported by the table to arrest movement thereof, means for vibrating said pin-members while engaged with the webs, and means for withdrawing said pin-members from the perforations to permit movement of the webs.

13. A device for controlling webs that are perforated longitudinally comprising a web supporting writing table across which the webs are adapted to be moved, means spaced beyond one end of said table for arresting the movement of the webs, a portion of said means adapted to enter the perforations in the portions of the webs not supported by the table and to be vibrated while engaged therewith, and means for withdrawing the perforation engaging portions to permit movement of the webs to the table.

14. A device for controlling webs that are perforated longitudinally comprising a web supporting writing table across which the webs are moved, and means spaced back of one end of said table and past which the webs are moved to the latter and including devices that arrest the movement of the webs of the table, said means being bodily adjustable towards and away from the table.

15. A device for controlling webs that are perforated longitudinally comprising a web supporting writing table across which the webs are moved, and means spaced back of the table and past which the webs are moved to the latter and including devices that enter web perforations in the portions of the webs not supported by the table and vibrate the

webs in the direction of their movement, said means being bodily adjustable towards and away from the table.

16. A device of the kind described comprising a writing table across which longitudinally perforated webs are moved a frame independent of and adjustable towards and away from said table and carrying the paper supply roll, and means on said frame adapted to arrest the movement of the webs to the table.

17. A device of the kind described comprising a writing table across which longitudinally perforated webs are moved, a frame bodily adjustable towards and away from said table and past which the webs are moved to the table and carrying the paper supply roll, and means on said frame and entering the perforation in the portions of the webs and not supported by the table and adapted to vibrate the webs in the direction of their movement.

18. A device of the kind described comprising a writing table across which longitudinally perforated webs are moved, a frame bodily adjustable towards and away from said table and past which the webs are moved to the table and carrying the paper-supply roll, means on said frame adapted to enter perforations in the portions of the webs not supported by the table and arrest their movement towards the table, and devices for vibrating said means in the direction of movement of the webs.

19. A device of the kind described comprising a writing table across which longitudinally perforated paper webs are moved, a frame bodily adjustable towards and away from said table having means for pendently supporting a supply of paper in roll form and having a cross-piece past which the paper is moved to the table, and means on the frame and coacting with the cross-piece to arrest the movement of the paper to the table.

20. A device of the kind described comprising a writing table across which longitudinally perforated paper webs are moved, a frame bodily adjustable towards and away from said table having means for pendently supporting a supply of paper in roll form and having a cross-piece past which the paper is moved to the table, and means on the frame and coacting with the cross-piece and entering perforations in the paper adapted to vibrate the paper in the direction of its movement to the table.

Signed at Chicago, in the county of Cook, and State of Illinois, this 7th day of January, 1926.

LOUIS JENSEN.
